United States Patent Office.

JAMES J. DE BARRY, OF BROOKLYN, NEW YORK.

Letters Patent No. 80,711, dated August 4, 1868.

IMPROVEMENT IN CHANGEABLE STENCIL-PLATES.

The Schedule referred to in these Letters Patent and making part of the same.

TO ALL WHOM IT MAY CONCERN:

Be it known that I, JAMES J. DE BARRY, of the city of Brooklyn, county of Kings, and State of New York, have invented certain new and useful Improvements in Changeable Stencil-Plates; and I do hereby declare that the following is a full and exact description thereof.

I will first describe what I consider to be the best means of carrying out my invention, and will afterwards designate the points which I believe to be new therein.

The accompanying drawings form a part of this specification.

Figure 1 represents the body or main plate, and

Figure 2 represents the same, with the stencil-strips properly mounted therein.

Similar letters of reference indicate like parts in all figures.

A is a plate, of brass or other suitable material, which is provided with an aperture, *a*, in which the letters which are to be stencilled are presented on the strips B B B B. These strips are formed of brass, or other suitable material, and are sufficiently thin to be flexible, and to allow of bending in the manner described.

The desired figures, letters, or other marks, which are to be stencilled, are put on the strips B B B B, so that, by shifting the strips endwise, in the plate A, the marks will be presented at the opening *a*.

So far as has been specifically described, my invention has been before known; but the means by which the strips were mounted in the plate, in the previous efforts in this direction, were objectionable, for the reason, among others, that the strips were necessarily held with their edges asunder, and this increased the spaces between the letters or figures to an inconvenient extent. There were, also, other evils attendant on the former arrangements, which my invention completely avoids.

My strips, B B, with their edges in contact each with its neighbor, form a smooth surface across which to rub the stencil-brush. Each strip is run under the stencil-plate A, immediately adjacent to the hole *a*, and is led up through a narrow slot in the plate *a*. These slots are peculiarly disposed. The slots D and E are nearer the hole *a* than the slots C and F, and they alternate in position. Each strip is led down again through the wide slots G H. It will be better understood from the figures than from a long written description. The effect of the entire structure is to hold the strips B B in contact with each other, and thus to present an improved construction and arrangement of the stencil-strips B B at the point where they are affixed, while providing a very strong and convenient construction of the whole, with a small expense for material and for labor.

I do not claim an adjustable stencil-plate, having a hole *a* and strips B B, adapted to be moved so as to present different figures or letters therein, except when the strips are mounted as herein specified; but, having now fully described my invention,

What I claim as new in stencil-plates, and desire to secure by Letters Patent, is as follows:

I claim the within-described slots C D E F, arranged relatively to the opening *a* and the strips B, the whole being adapted to form an adjustable stencil-plate, possessing the advantages and characteristics herein set forth.

JAMES J. DE BARRY.
